United States Patent Office.

WILLIAM MANTEY, OF NEW ORLEANS, LOUISIANA.

Letters Patent No. 77,994, dated May 19, 1868.

IMPROVEMENT IN TAPS FOR CUTTING SCREW-THREADS.

The Schedule referred to in these Letters Patent and making part of the same.

Be it known that I, WILLIAM MANTEY, of New Orleans, in the parish of Orleans, State of Louisiana, have invented a new Improvement in Screw-Cutting Tap; and hereby declare that the following is a full and exact description thereof, reference being had to the accompanying drawings, and to the letters of reference marked thereon, said drawings making part of this specification, in which—

Figure A is a longitudinal elevation,

Figure B a transverse section of *a b*, and

Figure C a regular delineation of the three cutting-sides.

Figs. A and B are natural size; the fig. C is double the size.

My tap is cut or chased and grooved in the ordinary way, but I take, commencing on the point, every other thread almost out, so that it is prevented from acting, and gives ample room for the cuttings, thereby lessening friction one-half. The last four round gangs of the thread I leave sharp, and give the nut to be cut a perfect finish, as will be seen in fig. A. Fig. C, the delineation shows that the threads Nos. 1, 3, 5, 7, 9, are prevented from action, having been filed out, while the threads Nos. 2, 4, 6, 8, will cut the screw with ease.

I do not claim the groove or number of grooves, nor the taper of the tap or screw, but

What I claim as my invention, and desire to secure by Letters Patent, is—

In the construction of taps for tapping nuts and the like, obliterating or diminishing every alternate cutting-thread, from the point of the tap back to near the termination of the cut portion, but leaving, in a space near said terminal portion, all the cutting-threads full and perfect, as herein described and shown.

New Orleans, January 21, 1868.

WILLIAM MANTEY.
